(57) **CLAIM**

The ornamental design for a pipe boot for flashing base as shown and described.

DESCRIPTION

FIG. 1 is a perspective view of a pipe boot for flashing base installed on a flashing base according to the present invention.

FIG. 2 is a perspective view of the pipe boot for flashing base of FIG. 1.

FIG. 3 is a top plan view of the pipe boot for flashing base of FIG. 1.

FIG. 4 is a bottom view of the pipe boot for flashing base of FIG. 1.

FIG. 5 is a side elevation view of the pipe boot for flashing base of FIG. 1; and,

FIG. 6 is an enlarged view of FIG. 5 of the pipe boot for flashing base of FIG. 1.

The broken lines show portions of the pipe boot for flashing base and environmental structure that form no part of the claimed design.

1 Claim, 6 Drawing Sheets
